UNITED STATES PATENT OFFICE.

ROBERT W. SCOTT, OF BOSTON, MASSACHUSETTS, ASSIGNOR, BY MESNE ASSIGNMENTS, TO SCOTT & WILLIAMS, INCORPORATED, A CORPORATION OF MASSACHUSETTS.

SECTIONAL-SPlicing MECHANISM FOR KNITTING MACHINES.

Application filed May 3, 1915. Serial No. 25,492.

My invention relates to knitting machines, one object being to provide improved and simplified devices adapted to knit fabrics, such for instance as seamless 5 stockings having sectionally spliced areas.

When attempting to knit fabrics of fine gauge upon ordinary latch needles of the prior art, it is observed that the fabric and especially that part of it knit with a short 10 length of stitch, is not capable of being made narrow to the desired degree by stretching lengthwise.

I have successfully avoided the said defect by changes in existing machines permitting use of needles having long hooks, 15 for instance needles of the type forming the subject of my Letters Patent No. 1,097,732, dated May 26, 1914.

My present invention relates to yarn-feeding devices capable of cooperation with such needles, and also capable of use with ordinary short hook needles, my said invention including in either use devices for knitting thereon sectionally spliced areas sharply defined at their edges. I have herein illustrated my invention, which is an improvement over the device shown, described and claimed in the application of H. L. Trudel and H. B. Dawson Serial No. 852,609, filed 20 July 23, 1914, as applied to a latch-needle knitting machine of the type described and claimed in my application Serial No. 746, 070 filed February 3, 1913, [Letters Patent No. 1,152,850, dated September 7, 1915], but 25 it will be understood that my invention is independent of the particular machine in which it may be utilized.

In the accompanying drawings,

Fig. 1 is a vertical section on the irregular plane 1—1 of Fig. 2;

Fig. 2 is a plan partly in section on line 2—2 of Fig. 1;

Fig. 3 is a diagram development of the cam ring and yarn feeding devices showing needles and paths taken by the needles during rotary knitting;

Fig. 4 is development showing a modified form of sectional splicing cam, and

Fig. 5 is a diagram showing one arrangement of needles having different kinds of butts.

The machine is provided with the usual needle cams and with needles, which as illustrated at 1 in Figs. 1 and 3 may be needles having comparatively long hooks 3,

and latches 5, which are comparatively short and situated at a relatively large distance from the tip of the needle. But it is not essential, when long-hooked needles are employed, that the hooks 3 shall be spring 40 hooks, as in my said patent, so long as the widest portions of the needles are at a substantial distance from their tips. For the usual purpose of separating the needles for knitting on a part only of the series, some 45 of the needles 1 have long butts 2 and some have short butts 4.

In order to supply yarn to such needles certainly and without the aid of yarn sinking means, when employing usual stitch-cams, as at 6, 7, 8, 9, Fig. 3, I have found it effective to insure that the yarn is fed with an increased lead, as compared with ordinary short hook latch needles, thus causing the yarn to lie under the points of hooks 3 and against the place for proper feeding of a considerable number of needles following a needle moving to land its hook over the yarn. In order to secure a sufficient lead when the machine is reciprocating, I have heretofore as explained in my application, Serial No. 39,887, filed July 14, 1915, provided for feeding the yarn for heels and toes from a yarn-guide or finger F¹ at a place central of the stitch-cams, all other 75 yarns being fed from a position in advance of said heel and toe finger, the stitch-cams, needle pickers and other adjuncts of the cam ring 370, 371 being rotated to bring a central plane A—A into coincidence with said 80 finger F¹. An extension 558 of the latch guard surface 550 protects the latches of needles advanced by the leading stitch cam 7.

Said other yarns are presented to and removed from the needles by movable guides 95 or yarn-fingers F², F³, F⁴, F⁵, actuated by thrust-bars 460 pattern-controlled by cams on drum 120.

In the machine described and claimed in said application of Trudel and Dawson, Serial No. 852,609, sharp entrance and exit of splicing yarn is obtained by causing a constant separation of the long and short butt needles at the region of the center cams, enabling the short butt needles to stand 100 above the others to take with certainty the splicing yarn presented and removed by an actuated yarn-finger. By reason of the rapid movement of the needles the splicing yarn-finger can not with certainty be 105 110

dropped low enough by timing its movement to enter its yarn under the hooks of the relatively long-hooked needles 1, and sufficient separation of such needles through 5 the longer distance between their tips and the opening under their hooks by a fixed center cam is not practicable. I have devised the following means for securing certain entrance and exit of the splicing yarn 10 with or without the cooperation of the usual vibrating splicing yarn finger.

One of the yarn fingers, preferably a yarn-finger F^2 next to the heel and toe finger F^1 , is provided with a foot 10 elevating its yarn-bore above plate 559 to such an extent as to deliver its yarn into the hooks of needles traveling in a normal path between cams 8 and 9 and beneath stitch cam 6. Means adjustable to cause all of the needles, or 15 selectively to cause the needles of the segment to be spliced only to take such a normal path are provided, said means causing all the needles except those for the spliced fabric to take a path with respect to which 20 F^2 is in an inoperative position and with respect to which the fingers F^3 , F^4 , F^5 are operative.

For greater certainty in securing a difference in the lead or angle of entrance of 25 the splicing yarn fed by finger F^2 and the body yarn, said body yarn may be fed from that finger F^2 furthest removed from splicing finger F^2 .

A preferred form of needle selecting means 30 may be constructed as follows:

Beneath the leading end of stitch cam 6 in a radial bore in cam ring segment 370 a short spindle 13 integral with a swivel cam 12 is journaled. Said cam 12 is thick 35 enough to engage the needles having long butts 2 only, and when in its upper or active position is housed in a recess 14 formed between the face of center cam 8 and standard 355 to which said cam 8 is attached. 40 In this position, cam 12 engages the long butts and retracts them on a path nearly parallel with the face of stitch cam 6 and ahead thereof, the tips of the long butt needles moving as shown at α , Fig. 3.

This place of retraction of the long butts 45 is sufficiently separated from yarn finger F^5 to cause the yarn therefrom safely to enter the hooks of the long butt needles, but is so close to the splicing yarn fed by finger F^2 as to cause said splicing yarn to lie against the face of hooks 3 of the long-butt needles, which miss taking the yarn, rotation of the needles causing the splicing yarn to float within the needles when 50 cast off.

Upon the approach of the leading short-butt needle, which will take a normal path, the splicing yarn is again operatively taken by all the short butt needles.

Cam 12 is spring held in the position

shown in Fig. 3 by a coil spring 16 reacting with an arm 18 of a collar 17 held by set-screw 19 on spindle 13.

A spring arm 20, carried by the thrust-bar 460 for yarn finger F^2 , for instance by 70 being adjustably held in a bore in a lug 21 on said bar by set-screw 22, takes under arm 18 to lift said arm and rock spindle 13 and cam 12 against spring 16 whenever the splicing yarn guide F is thrown to an 75 upper idle position.

The point of cam 12 when rocked downward may be housed in a recess 15 behind bottom center cam 9, the upper face of said cam 12 then lying beneath the normal 80 needle-path. Movement into and out of the operative position of Fig. 3 of said cam 12 normally occurs during passage of the short butt needles, but by reason of spring arm 85 20 and spring 16 movement of the thrust-bar and yarn guide F^2 during passage of the long-butts will not cause movement of cam 12 until the long butts engaging it have passed.

Suitable cams may be provided on drum 90 120 to position cam 12 and yarn finger F^2 operatively at the desired times, for instance when the ankle has been reached and after the heel has been formed, and it will be understood without further description that 95 the needles having short butts 4 will form reinforced fabric whenever said guide and cam are so positioned. Standard 355 may be cut away at 23 to permit segment 370 and cams 6, 7 and 12 to be moved out of contact 100 with the needles.

The purposes of the cam 12 may be served by modified constructions, for instance as shown in Fig. 4, in which a cam-slide 26 is 105 shown mounted to slide in an angular way formed behind top-center cam 8, said slide being outward of the faces of the cams far enough to clear the longer needle butts, and being provided with a cam proper 27 for moving the long-butts only, and with a hole 28 to receive a spring arm similar to arm 20 carried by the thrust-bar for the splicing yarn-finger for automatic positioning of slide 27 in the same manner as cam 12. 110

The extent of vertical separation of the 115 needles caused by the means for selectively positioning some of them to cooperate with a splicing yarn finger positioned to feed needles taking a normal path will depend upon the length of the hooks 3 of the needles.

During reciprocatory knitting the splicing yarn finger F^2 , the yarn fingers F^3 , F^4 , F^5 , and the cam 12 are held in their inoperative 120 positions, the normal path through the cams being free for passage of the short butts 4, and the long butts 2 if desired, to bring the needle-hooks into their normal relation with yarn finger F^1 in use at this time.

When the needles are divided into two sets 130

as described the marginal line of the spliced area coincides with the first and last low butt needle. It is sometimes desirable to have this margin extend into the high-butts 5 or instep needles, thus lending strength to the corner of the heel gore. This I accomplish by substituting for high butt needles at both ends of the set a given number of medium-butts needles 11, which will not be

acted upon by swivel cam 12 but will be acted upon as though they were long butt needles by the usual switch cam for throwing such needles out of action in making heels and toes.

15 The above described devices for feeding yarns are adapted without change to use with ordinary short-hook needles having butts of different lengths upon being elevated slightly with respect to the needles, 20 as will be understood without further illustration, so as to bring the tips of the needles and said yarn-feeding means into substantially the relation described and shown in Fig. 3 for said yarn-feeding means and the 25 points of the long hook 3 of needles 1.

These short hook needles having shorter butts will then be fed both with main yarn, as from finger F⁶, at a long lead, and with splicing yarn from finger F² at less lead.

30 All long butt needles after having taken main yarn will then be retracted when cam 12 is operative so far as to close their latches and at a place too much in advance of the splicing yarn to take it, or to encounter it 35 until said needles have passed cam 12 and traversed a part of the path α , and nearly rejoined the shorter butt needles. Needles so moved by the cam 12 are thus prevented, 40 their latches being closed, from afterward taking said yarn either by moving into contact with it, or by the preceding shorter butt needles, which have taken it, dragging said 45 yarn into contact with them.

It will now be apparent that the device of 45 moving one segment or set of needles only downward to a low point in advance of the stitch cam for all of the needles, in the presence of yarns guided to the needles at substantially different degrees of lead with 50 respect to the stitch-cam, is effective to cause the normally-operated needles only to take the yarn fed from the guide nearest the stitch-cam, and to cause the needles of said segment to reject said yarn, whatever the 55 construction of the needles.

It will be observed that the cam 12 or 57 or the like for so moving downward that segment of the needles which is not to receive the splicing yarn is in a relatively 60 low position in a vertical sense, so as to move the needles affected by it through a distance corresponding to a substantial part of the knitting stroke or movement which would otherwise be given the same needles 65 by the stitch cam 6.

For convenience of language I have herein referred to any of the described ineffective contacts between the needles and the splicing yarn, by means of which the splicing yarn is not taken in the hooks and is 70 positively excluded from the hooks of the needles, as an encounter of the needles with the splicing yarn in an inoperative relation thereto.

What I claim is:

1. A knitting machine having in combination needles, a stitch cam, means for delivering a body yarn and a splicing yarn from different distances in advance of said stitch cam to said needles, whereby said needles 80 normally take both of said yarns, and means in advance of said stitch cam for selectively moving certain of said needles only to a position in which said needles and said splicing yarn will come into contact in an inoperative relation.

2. A knitting machine having in combination latch needles, a stitch cam, guides for delivering a body yarn and a splicing yarn with different degrees of lead with respect 90 to said stitch cam, whereby said needles normally take both of said yarns, and means in advance of said stitch cam for selectively moving certain of said needles only to a low point whereby they come into contact with 95 said splicing yarn after their latches are closed, said means being active upon the needles after they have operatively taken said body yarn.

3. A knitting machine having in combination needles, a stitch cam, guides for delivering a body yarn and a splicing yarn with different degrees of lead with respect to said 100 stitch cam whereby needles worked by the stitch cam take both of said yarns, and a cam 105 acting ahead of the stitch cam for retracting certain of said needles only, after they have operatively received the body yarn, through a substantial part only of the same distance as the other needles are moved by 110 the stitch cam to draw loops after receiving the yarn, whereby said certain needles contact with but are prevented from operatively receiving the splicing yarn in their hooks.

4. A knitting machine having in combination needles, a stitch cam, means for delivering a body yarn and a splicing yarn from different points to said needles, whereby said needles normally take both of said yarns, and pattern controlled means for determining a different path for certain of said 115 needles at predetermined times, whereby said certain needles take the body yarn and encounter the splicing yarn inoperatively at 120 said times.

5. A knitting machine having in combination needles having long hooks, means for moving said needles in a path operative for knitting, and means for delivering a body 130 yarn in the hooks of all of said needles and

- 4
1. A splicing yarn against the faces of the hooks of certain of said needles only, whereby some of said needles operatively take both of said yarns, and means for determining a different path for said certain needles only, whereby said certain needles knit the body yarn and cast off the splicing yarn.
2. A knitting machine having in combination needles having long hooks, a stitch cam, a guide for delivering a body yarn and a movable yarn guide for delivering a splicing yarn in a different relation to said needles and the stitch cam whereby said needles normally take both of said yarns, and pattern controlled means for determining a different path for certain of said needles and moving said splicing yarn guide into operative position at predetermined times whereby said certain needles take the body yarn and cast off the splicing yarn at said times.
3. A knitting machine having in combination needles having latches and relatively long hooks, a stitch cam, means for delivering a body yarn and a splicing yarn from different points to said needles, whereby said needles operatively take both of said yarns, and means for determining a different path for certain of said needles only, whereby said needles take the body yarn in their hooks and take the splicing yarn against the faces of their hooks after their latches are closed in a position to be cast off at each passage of said stitch cam.
4. A knitting machine adapted for rotary and reciprocatory knitting and having needles, and leading and following stitch cams, means for feeding yarn for reciprocatory knitting, means for feeding yarn for sectional splicing during rotary knitting, and means for feeding a body yarn during rotary knitting from a point ahead of said splicing yarn feeding means, in combination with means for causing a series of said needles to be retracted to a relatively low point after taking said body-yarn and in advance of said following stitch-cam, whereby to encounter said splicing yarn inoperatively.
5. A knitting machine adapted for rotary and reciprocatory knitting having leading and following stitch cams and needles having relatively long hooks and short latches and a series of movable yarn guides, one end of said series being positioned substantially midway of said stitch cams, the remainder of said series being in advance thereof in the direction for rotary knitting, in combination with means for operatively positioning two of said series of yarn-guides to deliver yarn to the open hooks of needles actuated by said following stitch cam, and means for retracting a series of said needles to cause the faces of their hooks to receive one of said yarns.
6. A knitting machine having in combination needles in series having long and shorter butts, a stitch cam, movable guides for delivering a body yarn and a splicing yarn from different points separated in the direction of relative travel to said needles, whereby said needles operatively take both of said yarns when said guides are operatively positioned, a cam for retracting said long butt needles only through a part of their knitting stroke after they have received the body yarn, whereby to render the encounter of said needles with the splicing yarn inoperative, and means for adjusting said splicing yarn guide at predetermined times.
7. A knitting machine having in combination needles, yarn guides, a stitch cam, an adjustable cam for causing some of the needles acted upon by said stitch cam to pass one only of the yarn guides then in an operative position, without operatively receiving yarn, and means acting to move said last mentioned yarn guide into and out of operation, and to adjust said adjustable cam.
8. A knitting machine having in combination needles, a series of yarn-guides, a pattern-controlled connection for moving one of said yarn guides into and out of position to feed a splicing yarn to normally operated needles, a stitch cam, an adjustable cam for determining an abnormal path for some of the needles acted upon by said stitch cam whereby to prevent their knitting the splicing yarn, and means for adjusting said adjustable cam simultaneously with movement of said splicing yarn guide.
9. A knitting machine having in combination needles having long and shorter butts, a series of movable yarn-guides, a pattern controlled connection for moving one of said yarn guides into and out of position to feed a splicing yarn to all of said needles, a stitch cam, a cam adjustable into and out of position for retracting the long-butt needles only ahead of said stitch cam, whereby said needles are positioned to receive said splicing yarn in a position to be cast-off at said stitch cam, and means for adjusting said retracting cam upon movement of said connection.
10. A knitting machine having in combination needles, a yarn finger, a stitch cam, a spindle and a needle-cam thereon for determining in one position an abnormal path for some of the needles normally operated by said stitch cam, and means for simultaneously moving said yarn finger and rocking said spindle.
11. A knitting machine having in combination needles, a movable yarn finger, a stitch-cam adapted to remain in operative position during knitting, a movable needle cam cooperating with said stitch cam for determining in one position an abnormal path for some of the needles operated by said stitch cam, a pattern mechanism for

- automatically controlling the operation of the parts, and a single common connection between said pattern mechanism and said yarn guide and said movable needle cam, for automatic adjustment of said needle cam and yarn-finger by said pattern mechanism.
16. A knitting machine having long and short butt needles and a stitch-cam group comprising a stitch cam and center cams for 10 positioning said needles to take yarn, and a swinging switch cam for retracting the long-butt needles ahead of said stitch cam, said center cams being provided with recesses to receive said swinging cam, and means for holding the point of said swinging cam in either recess.
17. A knitting machine having in combination a thrust-bar, a movable yarn-finger actuated thereby, a movable needle-cam, and 20 a connection from said thrust-bar for moving said cam.
18. A knitting machine having in combination a thrust-bar, a movable yarn-finger actuated thereby, a movable needle-cam and 25 a yielding connection from said thrust-bar for moving said cam.
19. A knitting machine having in combination needles and cams defining a restricted passage for said needles, a swinging switch cam movable in said passage, spring 30 means for swinging said cam in one direction, and yielding means automatically actuated to swing said cam in opposition to said spring means, whereby said cam may not move in either direction until needles in contact with it have passed out of said passage.
20. In a circular knitting machine, in combination, a cam carrier segment, stitch cams and a swinging switch cam thereon, a relatively fixed standard, and center-cams 40 on said standard, said segment, stitch and swinging cams being movable with respect to said center cams, and operating means for said swinging switch cam permitting said movement.

In testimony whereof, I have signed my name to this specification.

ROBERT W. SCOTT.
